UNITED STATES PATENT OFFICE.

GEORGE A. SMITH AND MAX W. VOIGTMAN, OF ST. LOUIS, MISSOURI; SAID
VOIGTMAN ASSIGNOR TO SAID SMITH.

LAY-BOY.

SPECIFICATION forming part of Letters Patent No. 281,150, dated July 10, 1883.

Application filed September 12, 1882. (No model.)

To all whom it may concern:

Be it known that we, GEORGE A. SMITH and MAX W. VOIGTMAN, both of the city of St. Louis, in the State of Missouri, have invented a certain new and useful Improvement 5 in Lay-Boys, of which the following is a specification, reference being had to the accompanying drawings, forming part of the same.

Our improvement is primarily intended for 10 application to a paper-ruling machine, and it will be described in this connection. It may be applied to printing-presses, and in other situations where a sheet of paper is carried forward in front of its supporting device.

15 Our invention consists in the improvements hereinafter described, and pointed out in the claims.

Figure 1 illustrates our invention in side view. Fig. 2 is a transverse section at 2-2, 20 Fig. 1, one of the lower dropper-rolls being shown in section. Fig. 3 is a section at 3-3, Fig. 2. Fig. 4 is a detail end view of the rollers by which the paper is carried and their drive-pulleys. Fig. 5 is an enlarged detail 25 perspective of the adjustable bearing of the stretching-roll of the endless apron by which the ruled paper is presented to the dropper-rolls. Fig. 6 represents a transverse section of the paper sheet.

30 A represents the frame of a paper-ruling machine, B brackets, and C vertically-adjustable standards secured in the brackets by a dovetail groove and a set screw, D, passing through a slot, c, in the standard and screwing 35 into the bracket.

E is a bearing-box at the head of the standard, receiving the journal or gudgeon of the apron-carrying roller F.

G is the endless apron by which the ruled 40 paper is carried from the ruling-pens to the dropper-rolls. The endless apron passes over a roller, H, in near proximity to the lower dropper-rolls, M, and upper dropper-rolls, N, and in such relative position thereto that the 45 advancing edge of the paper is taken between the dropper-rolls and it is drawn forward thereby. Upon the roller H (or the shaft of the same) is a pulley, I, carrying a belt, J, which also passes over a pulley, K, upon the 50 carrying-shaft L of the lower dropper-rolls,

M. The relative sizes of the pulleys I and K are such that the shaft L has faster rotation than the roller H, so that the paper sheet is drawn forward on the endless apron at a greater speed than the apron travels to prevent one sheet interfering with another that is following it. The peripheries of the dropper-rolls M are of concave conical form and flush with the carrying-shaft on their inner sides, so that the paper O, when lying upon them 55 and pressed down by the rollers N, which have convex outer faces, will be curved up at the edges o without creasing, and will thus be made to assume the form of a shallow trough, with the sides gradually curved upward without being bent, having sufficient rigidity to prevent its bending downward, so that it is self-supporting throughout its length, and is supported clear of the receiving-box T until the last edge escapes from the dropping-rolls, 60 when it falls down upon the table, (or the other sheets thereon.) The lower rolls, M, taper off on their inner sides, forming annular knife-edges in close contact with the shaft, as shown in Fig. 2, so that the surfaces of the shaft and 65 roller fade into each other, and the shaft really forms a continuation of the rolls in all their positions, and both sets of rolls M and N are adjustable upon their shafts L and P, so that they can be moved sidewise to suit paper of 70 various widths—from the narrowest to the widest—and a continuous support from side to side for any width. The faces of the upper dropper-rolls, being convex, as shown, impart a curved edge to the paper without creasing 75 it.

m and n are set-screws by which the rollers M and N are held in position upon their shafts when in use.

The roller H and shafts L and P have journal-bearing on bracket arms R and S, respectively.

The operation is as follows: The sheets of paper are brought forward upon the endless apron G, and their front edges are seized by 95 the dropper-rolls M and N, which curve up the edges and rigidify the sheet, and it is held clear of the box T until it leaves the rolls M and N, when it drops down. The downward slope or inclination of the endless apron G 100

from the roller F to the roller H is such as to insure the feeding of the sheets of paper to the dropper-rolls with sufficient force to insure their proper engagement. The inclination may be increased by raising the roller F.

5 We claim as our invention—

1. In a paper-dropper, the lower rolls, M M, having concave conical inner sides formed with annular knife-edges, in combination with a shaft, L, the knife-edges forming, with the sides and shaft, a continuous smooth support for the paper, as set forth.

10 2. In a paper-dropper, the combination of

shaft L, lower adjustable rolls, M M, having concave conical inner sides formed with annular knife-edges, and the upper adjustable rolls, N N, having convex faces fitting the inner concave conical sides at their point of contact, the said lower rolls forming, with the shaft, a continuous smooth support from side to side for any width of paper, as set forth.

15 GEO. A. SMITH.

MAX W. VOIGTMAN.
